US00D401764S

United States Patent [19]

Apps et al.

[11] **Patent Number:** Des. 401,764[45] **Date of Patent:** **Dec. 1, 1998[54] **BOTTOM PORTION OF BOTTLE CASE**[75] Inventors: **William P. Apps**, Alpharetta; **Gerald R. Koefeda**, Atlanta, both of Ga.[73] Assignee: **Rehrig-Pacific Company, Inc.**, Los Angeles, Calif.[**] Term: **14 Years**[21] Appl. No.: **67,186**[22] Filed: **Feb. 28, 1997****Related U.S. Application Data**

[60] Division of Ser. No. 39,952, Jun. 7, 1995, Pat. No. Des. 378,249, which is a continuation-in-part of Ser. No. 18,317, Feb. 3, 1994, Pat. No. Des. 361,531, which is a continuation-in-part of Ser. No. 34,317, Feb. 1, 1995, Pat. No. Des. 379,717, which is a continuation-in-part of Ser. No. 919,376, Jul. 29, 1992, Pat. No. 5,529,176.

[51] **LOC (6) Cl.** ..... **03-99**[52] **U.S. Cl.** ..... **D3/318; D3/311**[58] **Field of Search** ..... D3/304-314, 318; D9/427; 206/427, 515, 519, 557, 564; 220/509, 513, 514, 516, 517, 669, 670, 672, 673, 676, DIG. 2, DIG. 12, DIG. 15[56] **References Cited**

OTHER PUBLICATIONS

- Exhibits G–J: Four photos of a bottle neck resting type crate without projections above the outer side walls.
- Exhibit K: One photo of a bottle neck resting type crate with different height outer side walls.
- Exhibit L: Four photos of an embodiment of Great Britain Patent Publication No. 2,158,044 & U.S. Design Patent No. D289,938.
- Exhibit M: Copy of a brochure illustrating an embodiment of GB No. 2,158,044/U.S. D28,938.
- Exhibit N: Copy of a brochure illustrating an embodiment of U.S. Patent No. 4,733,554 & an embodiment of GB No. 2,158,044/U.S. D289,938.
- Exhibit O: Four photos of an embodiment of U.S. Patent No. 4,344,530 to deLarosiere.
- Exhibit P: Two photos of an embodiment of U.S. Patent No. 4,700,837 to Hammett.
- Exhibit Q: Four photos of an embodiment of U.S. Patent No. 4,344,530 for 3-liter Pet bottles.
- Exhibit R: Four photos of a modified embodiment of U.S. Patent 4,700,837 for 3-liter Pet bottles.
- Exhibit S: Three photos of an embodiment of U.S. Patent No. 3,392,869 to Needt.
- Exhibit T: Four photos of a prior art crate of Rehrig–Pacific Company, Model No. PLBC–8–2L–HD.

Exhibit U: Four photos of a prior art crate of Rehrig-Pacific Company Model No. PLBC-6-2L-HD.

Exhibit V: Four photos of a prior art create of Rehrig-Pacific Company, Model No. PLBC-8-2L-PET-QD.

Exhibits W & X: Brochures including a PBC-6-2L (LO) crate for 2-liter bottle.

Exhibit Y: Brochure and photo, "Interlocking bottom grid. Cross stackable".
